UNITED STATES PATENT OFFICE.

THOMAS JANSEN, OF CHICAGO, ILLINOIS.

PREMIUM DEVICE FOR SAVINGS-BANKS.

1,186,792.

Specification of Letters Patent. Patented June 13, 1916.

Application filed July 15, 1915. Serial No. 39,981.

To all whom it may concern:

Be it known that I, THOMAS JANSEN, a citizen of the United States, residing at Chicago, in the county of Cook and State 5 of Illinois, have invented a certain new and useful Premium Device for Savings-Banks, of which the following is a specification.

This invention relates to coin receivers or banks such as are frequently distributed to the depositors of banking concerns for the collection of coins.

It is a common practice for banking concerns to distribute to depositors, especially to those having savings accounts, small coin 15 receptacles in which money is deposited from time to time as it is secured by the holder of the bank, the bank being taken at intervals by the depositor to the banking house, where it is opened by an official of 20 the bank, and the contents deposited to the credit of the patron.

The present invention is intended to stimulate and maintain an interest on the part of the depositor, and to encourage the collection 25 of coins for the savings account.

It consists substantially in the combination and arrangement of parts hereinafter described, illustrated in accompanying drawings, and more particularly set forth in the 30 claims.

In the drawings Figure 1 is a perspective of a coin collecting bank to which the present invention is applied; Fig. 2 is a vertical sectional view on line 2—2 of Fig. 1; Fig. 3 is a vertical sectional view on line 3—3 of 35 Fig. 2; Fig. 4 is a vertical sectional view on line 4—4 of Fig. 2; Fig. 5 is a fragmentary vertical sectional view on line 5—5 of Fig. 4; Fig. 6 is a fragmentary vertical sectional 40 view on line 6—6 of Fig. 4; Fig. 7 is a detail perspective of the operating pawl for the register wheel; Fig. 8 is a detail perspective of the holding dog for the key slide; Fig. 9 is a fragmentary vertical sectional 45 view, showing the key slide and the operating ratchet wheel for the control disk.

The embodiment of the invention shown in the drawings represents a rectangular metallic box or retainer, consisting of two 50 telescoping parts. The numeral 1 designates the inner one of these parts, which telescopes into an outer casing 2. Each of these parts forms a rectangular box having one open side, and when the two parts are telescoped 55 together, as shown best in Fig. 2, a complete closure is formed. Part 1 has secured

therein a locking device, designated generally by the numeral 3, with sliding bolts 4, which are arranged to be forced outwardly by a key into openings 5 in the outer case 2. When the parts are thus telescoped together and the locking devices 3 operated by a key, which is retained by the banking establishment, a closed receptacle is formed which cannot be opened by the depositor, but is accessible only to the person in charge of the key at the banking house. The receptacle itself is no part of the present invention, and any other form of lock box may be used.

At the side of the telescoping section 1 opposite that which carries the locking mechanism, is a wall or partition 6, secured to the side walls of section 1 by lugs 7 and screws 8. On the inner side of the partition 6 is fastened a coin chute 9 of a curved formation, to prevent access to the interior of the receptacle. An opening or slot 10 is provided at the upper end of the chute 9 for the reception of coins, and the lower end of 80 the chute discharges downwardly, as shown at 11, into the receptacle.

Projecting from the side of the partition 6, opposite the chute 9, is a short stub shaft 12, on which a control disk 13 is mounted 85 for free rotation. Secured firmly to disk 13 to rotate therewith, is a ratchet wheel 14, shown in Figs. 4 and 6, and two notches 15 are provided in the periphery of the disk for a purpose to be described. Projecting 90 from the partition 6, on the same side thereof as the control disk 13, is a pair of pins 16, on which is slidably mounted a key 17. A coil spring 18 is secured to the key 17, and normally draws the key upwardly in a way which will be apparent from Fig. 4 of the drawing. Pivotedly mounted on a pin 19, secured to the partition 6, is a holding dog 20, having a catch 21 arranged to enter a notch 22 in the edge 100 of the key slide 17, and retain this slide in its lower position against the tension of the spring 18. The coil spring 23 normally forces the catch 21 resiliently into contact with slide 17 in a way to cause it to enter 105 the notch 22 whenever the notch is in position to receive the catch. An elongated opening 24 is cut through the partition 6 as shown in Figs. 3 and 4, and a pin 25, carried by the dog 20, projects through the opening 24 into a position opposite one edge 110 of the discharge opening 11 of the coin

chute 9 as best shown in Figs. 2 and 3. As will be seen from Fig. 3, when a coin of a diameter equal to the width of chute 9 is discharged from the opening 11, the edge 5 of the coin will strike the pin 25, and force it to the left as shown in Fig. 3, and thus move the catch 21 out of engagement with the notch 22, and permit the key slide 17 to be drawn upwardly by the spring 18. Pivotally mounted on slide 17 by means of a pin 26, is a pawl 27, normally held in the position shown in Fig. 9 by the spring 28. As will be apparent from Figs. 4 and 9, during the upward movement of the slide 15 17 referred to above, the pawl will move freely over the teeth of the ratchet wheel 14. If, however, the key 17 is moved downwardly by pressure on the finger piece 29, which extends outside of the casing, the 20 pawl 27 will engage one of the teeth in the ratchet wheel 14, and give this wheel, together with the control disk 13, a spinning rotation about the pivot 12. The amount of this rotation will depend, of course, upon 25 the manner in which the finger piece 29 is struck.

Mounted on the pivot 30, carried by the partition 6 for oscillation thereon, is a bar 31, provided with a slide 32, which extends 30 through the casing, and carries a finger piece 33 in the outside of the casing as shown in the drawing. Pivotally mounted on a projection 34 at the end of the bar 31 is an 35 operating pawl 35, and a coil spring 36 is arranged resiliently to hold the pawl 35 in the position shown in Fig. 4. A coil spring 37 normally holds the bar 31 in its uppermost position, as shown in Fig. 4. Rotatably mounted on a stub shaft 38, at the 40 up-per left hand corner of the partition 6, as shown in Fig. 4, is a register wheel 39, having rigidly secured thereto, for rotation therewith, a ratchet wheel 40. The teeth of 45 the ratchet wheel 40 are arranged in the path of movement of the projecting lug 41 on the operating pawl 35, when this pawl is swung downwardly by pressure on the finger piece 33. The ratchet wheel and operating pawl are so proportioned that the 50 wheel is rotated a distance corresponding to one tooth on the ratchet wheel for each oscillation of the pawl carrying bar 31. A spring detent 42 is pivotally mounted on the partition 6, and is resiliently held in position 55 to prevent reverse movement of the ratchet wheel 40 by means of the spring 43. The register wheel 39 is provided on the face thereof, next the outer wall of the casing, with a series of numerals extending 60 entirely around the wheel. One numeral is provided for each tooth on the ratchet wheel 40. The number of these teeth and numerals of course is determined by the requirements of the service to which the bank is put.

65 Carried by the pivot 45 shown at the lower

right hand corner of Fig. 4 is an oscillatory bar 46, which has pivotally mounted near the end thereof, opposite the pivot 45, a pawl 47. A spring 48 normally tends to rotate the pawl 47 in a clockwise direction 70 about its pivot 49, and a spring 50 normally draws the bar 46 and the pawl 47 upwardly about the pivot 45. The inner edge of the pawl 47 is provided with a cam surface 51, which is arranged to contact with a pin 52 75 projecting from the partition 6. As shown in Fig. 4, the pin 52 holds the pawl 47 out of contact with the ratchet wheel 14 when this pawl and the bar 46 are in their uppermost position. A link 52' connects the pin 53 on the bar 31 with the pin 54 on the bar 46. The lower end of the link 52', which cooperates with pin 54, is provided with an elongated slot 55, to permit of a slight movement of the bar 31 independently of the bar 85 46. The pin 56, carried by the bar 31, projects laterally into a position extending over the periphery of the disk 13 as shown in Figs. 4 and 6, so that normally the disk 13 will prevent oscillation of the bar 31 about 90 its pivot 30. If, however, one of the notches 15 is in position to register with the pin 56, it will be apparent that the bar 31 may be moved downwardly about the pivot 30 by pressure on the finger piece 33. An opening 95 60 is provided in the wall of the casing opposite the register wheel 39, in position to disclose to view one of the numerals—the uppermost one as shown in the drawing, on the wheel 39. A second opening 61 is provided in the casing opposite the face of the control disk 13, and the control disk 13 is provided with colored portions 62, arranged to register with the opening 61 in the wall 100 of the casing whenever one of the notches 15 registers with the pin 56 on the bar 31. The openings 60 and 61 are covered with glass or other transparent material as shown in Figs. 5 and 6, to prevent access to the 105 interior of the casing.

110 From the foregoing description it is believed that the operation of the invention may now be understood. The bank is delivered to the depositor with the two telescoping sections fitted together, and locked in place by the locking mechanism 3 and sliding bolts 4, slots 65 being provided in the outer section 2 to accommodate the finger pieces 29 and 33 during the opening and closing of the receptacle. When the bank is 115 delivered to the depositor, the key slide 17 is depressed and locked in its lower position by the dog 20. When a coin of the proper size is inserted in the slot 10 by the depositor it descends through chute 9, and strikes the pin 5 as it is discharged from the mouth of the chute 11 into the receptacle. When the coin strikes the pin 25, it moves the dog 20 about its pivot 19 a sufficient distance to disengage the catch 21 from the notch 22, and 120 125 130

the key slide 17 is thus freed, and is drawn upwardly by the spring 18. The depositor may then strike the finger piece 29, and force the slide 17 downwardly again into position,

5 to be held by the dog 20. As the slide moves downwardly the pawl 27 will strike one of the teeth of the ratchet wheel 14, and give the ratchet wheel, together with the control disk 13, a spinning rotation about 10 the pivot 12 as an axis. The disk 13 will continue to rotate for some time, and until it is brought to rest by the friction on the pivot pin 12 and the friction of the air against the rotating disk. When the disk 15 finally comes to rest, in most cases the uppermost periphery of the disk will be in position to prevent movement of the pin 56. If, however, the disk comes to rest with one 20 of the notches 15 in registration with the pin 56, the bar 31 will be free to move downwardly about the pivot 30 as an axis when the depositor presses the finger piece 33 in a downward direction against the tension of 25 the spring 37. The fact that the notch 15 is in registration with the pin 56 is disclosed to the depositor by one of the colored portions 62 showing through the opening 61 in the casing. When the depositor sees one of 30 these colored portions opposite the opening 61 he knows that it is possible for him to depress the finger piece 33, and the depression of this finger piece as previously explained rotates the register wheel 39 one 35 point, which fact will appear to the depositor by the change of the numeral which is visible through the opening 60, to the numeral of the next higher denomination.

As the bar 31 moves downwardly under pressure on the finger piece 33, the link 52' 40 transmits downward movement to the bar 46, which in turn carries the pawl 47 in the same direction. As the pawl 47 descends, it is permitted by the cam face 51 to swing inwardly into position to contact with the teeth of the ratchet wheel 14. On the return or upward movement of the parts mentioned, the pawl 47 will strike one of the teeth on the ratchet wheel 14 before it is thrown outwardly by the pin 52, and after 45 the pin 56 has moved out of the notch 15. This operation of the pawl 47 will give the disk 13 a rotary motion, which will move the notch 16 out of registration with the pin 56, and thus prevent further operation of the 50 finger piece 33 and the registration wheel 39. It will thus be seen that for each coin deposited the operating mechanism for the disk 13 is released, and the depositor is given one opportunity for spinning the control 55 disk, and a chance of the disk's stopping in position to permit the rotation of the registration wheel into position to register one more point. When the bank is delivered to the depositor, it is explained to him that he 60 will be given credit on his bank account for

a certain sum for each point registered and showing through the opening 16. The credit thus given is additional to the money deposited in the bank, and is a premium for the purpose of encouraging savings de- 70 posits. It is apparent, of course, that the chance which a depositor has, whenever he makes a deposit, of obtaining a premium, will create and maintain an interest in his savings account, and encourage him in advertising to others the banking establishment which supplies its customers with banks provided with the present invention. Thus this invention serves the double purpose of encouraging savings accounts on the 80 part of the depositor, and of advertising the business of the banking establishment which distributes the banks provided with the invention.

I claim:

1. In combination, a receptacle for the accumulation of savings, register mechanism, a chance device for controlling the operation of said register mechanism, and means controlled by a coin as it is placed within 90 said receptacle for operating said chance device.

2. In combination, a receptacle for the accumulation of savings, means for rendering the contents of said receptacle inaccessible 95 to the holder thereof, register mechanism, means operable in accordance with chance for controlling said register mechanism, and a device rendered operable by a coin deposited in said receptacle for operating 100 said controlling means.

3. In combination, a receptacle for the accumulation of savings, a register device, mechanism operable in accordance with chance for controlling said register device, 105 and means for operating said register control device rendered operable when a coin is deposited in said receptacle, to afford the depositor the chance given by the operation of said control mechanism of being permitted to operate said register device.

4. In combination, a receptacle for the accumulation of savings, an indicator, mechanism for operating said indicator, a device arranged, when in certain position, to prevent operation of said mechanism, and to permit operation thereof when in other positions, the position which said device assumes when set in operation being controlled by the laws of chance, and means 115 for operating said device rendered operable when a coin is inserted in said receptacle.

5. In combination, a receptacle for the accumulation of savings, a register device, and coin-controlled means for normally preventing operation of said register device, by which means said register device may or may not, according to chance, be rendered operable when a coin is deposited in said receptacle.

6. In combination, a coin savings receptacle, a register device carried by said receptacle, mechanism for operating said register device, a rotatable member adapted in certain positions to prevent operation of said mechanism, and in other positions to permit operation of said mechanism, the position at which said rotatable device comes to rest after being set in motion depending upon the laws of chance, and means rendered operable by the deposit of a coin in said receptacle for rotating said device.

7. In combination, a coin savings receptacle, a chance device mounted on said receptacle, a slide for operating said chance device and means for holding said slide in inoperative position, and for releasing said slide whenever a coin is deposited in said receptacle.

8. In a savings device, a receptacle, means for rendering the contents of said receptacle inaccessible to the holder thereof, a register device, means operable according to chance for controlling said register device, and coin-controlled mechanism for permitting a single operation only of said control device for each coin deposited in said receptacle.

9. In combination, a receptacle for the accumulation of savings, a register device connected with said receptacle, and coin-controlled means operable according to chance, by which a depositor may or may not be enabled to record one point on said register device for each coin deposited in said receptacle.

10. In a device of the character described, a receptacle for the accumulation of savings, a register device, operating mechanism for said register device, means for normally preventing operation of said operating mechanism, but adapted in certain positions to permit operation thereof, and means controlled by the insertion of a coin in said receptacle for moving said operation preventing means to afford a chance of said means assuming a position to permit operation of said register operating device.

11. In a device of the character described, a receptacle for the accumulation of savings, a register wheel, mechanism for moving said wheel one point at a time, means adapted in one position to permit operation of said register moving mechanism, and a device for moving said last named means out of said position after an operation of said register moving means.

12. In combination, a receptacle for the accumulation of savings, a register device, means for operating said register device, a device for controlling said operating means, and adapted in certain positions to prevent movement of said operating means, and in other positions to permit said movement, means controlled by a coin inserted in said

receptacle for causing said control device to assume a position by chance, and means for changing the position of said control device after an operation of said register operating mechanism.

13. In combination, a receptacle for the accumulation of savings, a device, operable according to the laws of chance, carried by said receptacle, mechanism for operating said device, means for normally holding said operating mechanism in inoperative position, and arranged to release said mechanism whenever a coin is inserted in said receptacle.

14. In combination, a receptacle for the accumulation of savings, a register device, means controlled by chance for rendering said register device operable, and means for indicating when said chance control means is in position to permit operation of said register device.

15. In combination, a receptacle for the accumulation of savings, a control device, operable in accordance with the laws of chance, carried by said receptacle, means controlled by the insertion of a coin in said receptacle for operating said chance control device, and means for recording results of the operation of said chance control device.

16. In combination, a receptacle for the accumulation of savings, a rotary wheel carried by said receptacle, a register wheel carried by said receptacle, means controlled by said rotary wheel for operating said register wheel, and means for permitting a single operation only of said rotary wheel whenever a coin is inserted in said receptacle.

17. In combination, a receptacle for the accumulation of savings, a register wheel carried by said receptacle, a key arranged, at each operation, to move said register wheel one point, means for normally preventing the operation of said key, a second key for operating the said last named means, a device for normally holding said second key in inoperative position, and arranged to release said key whenever a coin is inserted in said receptacle.

18. In combination, a receptacle for the accumulation of savings, a register device carried by said receptacle, a key for operating said register device, mechanism for controlling according to the laws of chance said register device operating key, a second key arranged to operate said mechanism, means for normally holding said second key in inoperative position, and for releasing said key when a coin is inserted in said receptacle, and means for causing said key holding means to render said second key inoperative after each operation thereof.

19. In combination, a receptacle for the accumulation of savings, a register device

- carried by said receptacle, means for operating said register device, a chance device for controlling said register device operating means, mechanism for operating said 5 chance device, coin-controlled means for rendering said mechanism operable when a coin is inserted in said receptacle, and for rendering said mechanism inoperable after each operation thereof.
- 10 20. In combination, a receptacle for the accumulation of savings, a numeral wheel carried by said receptacle, a key for operating said numeral wheel and adapted to move said wheel one point for each operation of said key, a freely rotatable disk arranged, in certain positions, to prevent operation of said key, and in certain other positions to permit operation of said key, a second key
- 15 for rotating said disk, means for normally holding said second key in inoperative position and for releasing said key to permit a single operation thereof when a coin is inserted in said receptacle but arranged to prevent a repetition of said operation, and means for changing the position of the control disk for said register operating key after each operation of said key.
- In testimony whereof I have signed my name to this specification, in the presence of two subscribing witnesses, on this 9th day 25 of July, A. D. 1915.

THOMAS JANSEN.
